I. V. EDGERTON

TAIL LIGHT FACEPLATE

Filed June 6, 1923

Inventor

Israel V. Edgerton,

By S. N. Gillis

Attorney

UNITED STATES PATENT OFFICE.

ISRAEL V. EDGERTON, OF OAK PARK, ILLINOIS.

DESIGN FOR A TAIL-LIGHT FACEPLATE.

Application filed June 6, 1923. Serial No. 6,423. Term of patent 3½ years.

To all whom it may concern:

Be it known that I, ISRAEL V. EDGERTON, a citizen of the United States, residing in the city of Oak Park, county of Cook, and State of Illinois, have invented a new, original, and ornamental Design for Tail-Light Faceplate, of which the following is a specification, reference being had to the accompanying drawing, forming part thereof.

The figure is a face view of a tail light face plate showing my new design.

I claim:

The ornamental design for a tail light faceplate, as shown.

ISRAEL V. EDGERTON.
